UNITED STATES PATENT OFFICE

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

LOOM DOBBY

Application filed August 13, 1929. Serial No. 385,507.

This invention relates to a doby by which the movements of harness jacks or other devices in a loom may be determined. It is customary in such dobbies to provide a pattern chain built up of substantial and material elements, such as chain rolls or pegged cross bars.

It is the object of my invention to provide a doby in which the indications may conveniently be derived from a perforated strip of paper, which may be easily and cheaply produced of any desired length and which may be stored in a roll of small dimensions.

A further object of the invention is to provide novel elements cooperating with the perforated strip, by which the indications are transmitted to the lifter levers without causing the weight of the fingers at any time to be sustained by the perforated strip.

My invention further relates to arrangements and combinations of parts which will be hereinafter described and more particularly pointed out in the appended claims.

A preferred form of the invention is shown in the drawings in which

Fig. 1 is a side elevation of a doby embodying my improvements;

Fig. 2 is a sectional plan view, taken along the line 2—2 in Fig. 1;

Fig. 3 is a sectional side elevation, taken along the line 3—3 in Fig. 2;

Fig. 4 is a detail side elevation to be described;

Fig. 5 is a side elevation of a part of the perforated sheet and its supporting cylinder, with the indicating members shown in section;

Fig. 6 is an enlarged side elevation of certain parts shown in Fig. 3, and

Figs. 7, 8 and 9 are diagrammatic views, showing the cooperation of certain parts under different conditions.

Referring particularly to Figs. 1 and 2, I have shown a doby comprising a frame 20 supporting the usual rock shaft 21 on which is mounted a lever 22 connected by links 23 to upper and lower knife bars 24 and 25. The shaft 21 is regularly oscillated by actuating mechanism, not shown.

Upper and lower doby fingers 26 and 27

are pivoted at the opposite ends of levers 28, which in turn are pivoted to the usual harness jacks 29 or to other elements to be actuated thereby. Lifter levers 30 and 31 (Fig. 3) are mounted in the lower part of the doby frame 20, the levers 30 controlling the upper fingers 26 through lifter rods 32 and the levers 31 directly engaging the lower fingers 27.

The levers 30 and 31 are provided with segmental slots 35 (Fig. 8) for a purpose to be described, but otherwise the parts thus far described are of the common commercial construction.

A pattern cylinder 40 is mounted to rotate below the frame 20 and is provided with a worm gear 41 which is intermittently advanced by a dwell worm 42 on a continuously rotated drive shaft 43. A perforated record sheet S is mounted on a cylinder 40 and is provided with perforations 45 spaced for alignment with holes 46 in the cylinder 40. An additional set of holes 47 near each edge of the sheet S may be caused to cooperate with pegs 48 in the cylinder 40 to preserve the correct alignment of the perforations 45 with the holes 46 in the cylinder.

Indicating members 50 are pivoted at one end on a cross rod 51, mounted in vertically slideable supporting members 52. At their lower ends, the members 52 are guided by studs 54 (Fig. 3) projecting into slots 55 in said members, and at their upper ends the members 52 are provided with slots 56 embracing a cross shaft 57 on which two pairs of actuating cams 58 and 59 are mounted.

The cams 58 are effective to intermittently raise and lower the members 52 which support the cross rod 51 on which the indicating members 50 are pivoted. The cams 59 act through links 60 to rock a pair of levers 62, pivoted at 63 and supporting a segmental knife bar 64 at their lower ends.

The indicating members 50 are provided with depending studs 65 (Fig. 3) adapted to register with the holes 46 of the cylinder 40 when the cylinder is at rest in its successive operative positions. The free ends of the indicating members 50 are beveled as indi-

cated at 66 (Fig. 7) and extend adjacent the path of movement of the knife bar 64.

The knife bar 64 is not rigidly attached to the lower ends of the levers 62 but is pivoted thereon at 68 and is provided with lugs 69 engaging abutments 70 on the levers 62. Springs 71 (Fig. 3) hold the knife bar 64 yieldingly in the position shown in Fig. 7 but permit a slight clockwise yielding movement of the knife bar under certain conditions to be described.

A fixed cross rod or support 73 (Fig. 3) extends under the beveled ends of the indicating members 50 and provides a pivotal support for rocking movement thereof under certain conditions.

Having described the details of construction of my improved dobby, the method of operation thereof is as follows:

The cams 58 act to raise the supporting members 52 and cross rod 51 to the position shown in Fig. 8 just prior to an angular advance movement of the cylinder 40. In this position the studs 65 on the members 50 clear the perforated sheet S. The cylinder 40 is then given a quarter revolution, bringing the next successive series of perforations 45 in alignment with the studs 65. The cams 58 then permit the supporting members 52 and cross rod 51 to move downward to the position shown in Fig. 7, so that the studs 65 may enter the perforations 45 or be supported on unperforated portions of the paper.

If the studs enter perforations 45 and the holes 46 underlying the same, the indicating members 50 take the position indicated in Fig. 7, in which the beveled ends 66 of the members 50 are out of the path of movement of the segmental knife 64. If, however, the studs 65 engage unperforated portions of the sheet S, the indicating members 50 will be rocked about the studs 65 as pivots to the position shown in Fig. 9, with the beveled portions 66 projected into the path of the segmental knife 64. The cams 59 then cause the knife 64 to be advanced, engaging the members 50 which are in the position indicated in Fig. 9 and causing the corresponding lifter levers to be raised, thereby positioning the associated dobby fingers for engagement by the actuating knife bars 24 and 25. Whenever a perforation 45 occurs in the record sheet S, however, the corresponding indicating members 50 assume the inoperative position indicated in Fig. 7 and the corresponding indicator levers remain at rest in normal position.

If for any reason the lifter levers 30 or 31 are not free to move when the segmental knife 64 is swung upward, the knife will yield slightly, as indicated in Fig. 6, upon engagement with the ends 66 of the members 50, and breakage of parts will thus be prevented.

Having thus described my invention and the advantages thereof, I do not wish to be

limited to the details herein disclosed, otherwise than as set forth in the claims, but what I claim is:—

1. In a dobby, a pattern cylinder having holes therein, means to intermittently advance said cylinder, a record sheet mounted on said cylinder and having transverse rows of perforations therein adapted to register with said holes, a plurality of dobby fingers, lifter mechanism therefor, a plurality of indicating members, a support on which said members are pivoted, and means to give said support intermittent regular movements, the resultant movement of said members being modified by the presence or absence of perforations in said record sheet.

2. In a dobby, a pattern cylinder having holes therein, means to intermittently advance said cylinder, a record sheet mounted on said cylinder and having rows of perforations therein adapted to register with said holes, a plurality of dobby fingers, lifter levers therefor, an actuating member normally freely movable relative to said lifter levers, and an indicating member for each lifter lever, each indicating member having an intermediate portion cooperating with the record sheet and one end of each member being positioned in the path of said actuating member by engagement of said intermediate portion with an unperforated part of said record sheet, and thereby rendering said actuating member effective to raise the lifter lever associated with said indicating member, and the opposite end of each indicating member being movable intermittently and regularly to cause said intermediate portions to engage the record sheet or a perforation therein.

3. In a dobby, a pattern cylinder having holes therein, means to intermittently advance said cylinder, a record sheet mounted on said cylinder and having rows of perforations therein adapted to register with said holes, a plurality of dobby fingers, lifter levers therefor, an actuating member normally freely movable relative to said lifter levers, and an indicating member for each lifter lever, each indicating member having an intermediate portion cooperating with the record sheet and one end of each member being positioned in the path of said actuating member by engagement of said intermediate portion with an unperforated part of said record sheet, and thereby rendering said actuating member effective to raise the lifter lever associated with said indicating member, and the opposite end of each indicating member being movable intermittently and regularly to cause said intermediate portions to engage the record sheet or a perforation therein, said indicating member being inoperative when a perforation in said record sheet is presented thereunder.

4. In a dobby, a pattern cylinder having

holes therein, means to intermittently advance said cylinder, a record sheet mounted on said cylinder and having rows of perforations therein adapted to register with said holes, a plurality of dobby fingers, lifter levers therefor, an actuating member normally freely movable relative to said lifter levers, and an indicating member for each lifter lever, each indicating member having a portion cooperating with the record sheet and another portion of each member being positioned in the path of said actuating member by engagement of said first portion with an unperforated part of said record sheet and thereby rendering said actuating member effective to raise the lifter lever associated with said indicating member, said actuating member being adapted to yield relative to said indicating member if movement of said member is prevented.

5. In a dobby, a pattern cylinder having holes therein, means to intermittently advance said cylinder, a record sheet mounted on said cylinder and having rows of perforations therein adapted to register with said holes, a plurality of dobby fingers, lifter levers therefor, an actuating member normally freely movable relative to said lifter levers, a movable support to which one end of said 25 indicating member is pivoted, a fixed support on which the other end of said member rests, and means to raise and lower said movable support.

6. In a dobby, a pattern cylinder having holes therein, means to intermittently advance said cylinder, a record sheet mounted on said cylinder and having rows of perforations therein adapted to register with said holes, a plurality of dobby fingers, lifter levers therefor, an actuating member normally freely movable relative to said lifter levers, a movable support to which one end of said indicating member is pivoted, a fixed support on which the other end of said member rests, and means to raise and lower said movable support in timed relation to the movement of said actuating member.

7. In a dobby, a pattern cylinder having holes therein, means to intermittently advance said cylinder, a record sheet mounted on said cylinder and having rows of perforations therein adapted to register with said holes, a plurality of dobby fingers, lifter levers therefor, an actuating member normally freely movable relative to said lifter levers, a movable support to which one end of said indicating member is pivoted, a fixed support on which the other end of said member rests, and a cam operable to raise and lower said movable support in timed relation to the movement of said actuating member.

In testimony whereof I have hereunto affixed my signature.

ALBERT A. GORDON.
